Primary Examiner—Doris V. Coles*Assistant Examiner*—Elizabeth A. Albert(74) *Attorney, Agent, or Firm*—Phillip E. Walker(57) **CLAIM**

What is claimed is the ornamental design for a rail and fence bracket apparatus, as shown and described.

DESCRIPTION

FIG. 1 is a perspective front view of the rail and fence bracket apparatus showing my new design;

FIG. 2 is a front elevation view of the rail and fence bracket apparatus shown on a reduced scale;

FIG. 3 is a left side elevation view of the rail and fence bracket apparatus shown on a reduced scale;

FIG. 4 is a back elevation view of the rail and fence bracket apparatus shown on a reduced scale;

FIG. 5 is a right side elevation view of the rail and fence bracket apparatus shown on a reduced scale;

FIG. 6 is a top elevation view of the rail and fence bracket apparatus shown on a reduced scale;

FIG. 7 is a bottom elevation view of the rail and fence bracket apparatus shown on a reduced scale; and,

FIG. 8 is an alternate perspective front view of the rail and fence bracket apparatus shown on an enlarged scale.
